FIG. 1

FIG. 2

Thomas E. Graham, INVENTOR.

BY Loyd J. Miller,

ATTORNEY

UNITED STATES PATENT OFFICE

2,452,455

LADDER ATTACHMENT

Thomas E. Graham, Oklahoma City, Okla., assignor of one-third to Loyal J. Miller, Oklahoma City, Okla.

Application July 23, 1945, Serial No. 606,611

4 Claims. (Cl. 248—238)

1

My invention relates to brackets to be attached to ladders, and more particularly to ladder brackets which provide platform space, and will act as a support for scaffolds.

The prime object of the invention is to provide a ladder bracket which may be supportably attached to any usual ladder, and when so attached, will provide a standing platform for a worker.

Another object is to provide an article of this class, which may be attached one to each of two spaced leaning ladders, and when so attached, the two will act as a support for the ends of two scaffold boards.

A further object is to provide an article of this class which may be easily and quickly attached to a ladder, without the use of any tools or mechanically operated attaching or clamping mechanism, and when so attached, will offer a strong and safe support for a workman.

A still further object is to provide a bracket for the purpose set forth, which is so designed that it may be cut or die-stamped from a single flat sheet of material, and which may then be formed into the completed article merely by proper bending.

Further objects will be apparent from the following description when taken in conjunction with the accompanying single sheet of drawings, wherein:

Figure 1 is a diagrammatic view of two usual ladders leaning against a wall, and showing in perspective, one article of the invention operatively installed upon each ladder; and

Figure 2 is a perspective view of the device operatively installed upon a usual rung-type ladder.

Like characters of reference designate like parts in the figures wherein they occur.

In the drawings:

The reference numeral 1 indicates a vertical wall against which are leaning the upper ends of two spaced ladders 2. The ladders are of usual type, each consisting of parallel side members 3 between which are rigidly mounted vertically spaced horizontal rungs 4.

The article of the invention is adapted to be installed upon and to be supported by the rungs 4 of the ladder, and consists of the following described integral parts or portions.

A horizontal flat upper platform 10; a similar lower platform 11; and a straight frame member or connector 12 attaching the two platforms rigidly together in spaced relation. The platforms 10 and 11 are substantially identical, but extend horizontally from opposite sides of the frame

2

member 12, and the outer end of each is provided with two arcuate and downwardly extending hooks 13. In the preferred embodiment shown, the platforms are shown as having their outer portions bifurcated by a V-shaped notch 14, but if desired, the notch could well be eliminated, and the hooks 13 of each platform could extend entirely across the platform.

The article is installed by merely engaging the hooks 13 over two rungs 4 of the ladder, with the frame member 12 passing through the ladder adjacent an intermediate rung. The frame member 12 is provided with a hook 15 for engagement over the intervening rung, as best shown in Fig. 2.

When thus installed, the four hooks 13 and the single hook 15 act to prevent any rocking or swinging movement of the device. The platform 10 may be used as a standing or sitting surface for a workman, and the lower platform 11 may be used to support working materials such as paint containers, caulking material, and the like.

When used as a scaffold support, one of the devices is installed upon each of two spaced ladders (Fig. 1), and a board 16 may then be supported by the two. The upper platforms are each equipped with an upstanding lug or flange 17 to prevent lateral slipping of the board.

Obviously certain modifications of the article could well be made without detrimentally affecting its efficiency, and without avoiding the principle upon which it is constructed nor the principle upon which it functions, and I therefore do not wish to be limited to the specific embodiment shown and described herein, further than I am limited by the scope of the appended claims.

While not so shown in the drawings, the hook 15 and the lug 17 could well be cut from the body of the frame member 12 and the platform, respectively. This would permit the entire article to be die-stamped from sheet material at a single operation.

I claim:

1. As an article of manufacture, a unitary structure including: two vertically spaced horizontal platforms, the upper one partially overlying the lower one; a connector extending between opposite ends of said platforms and rigidly holding them with their upper surfaces in parallel relation; a depending hook at the free end of each platform; and an outwardly extending downwardly projecting stabilizing hook intermediate the ends of said connector.

2. Structure as specified in claim 1, and an upstanding flange carried by the connected end of the upper platform.

3. As an article of manufacture, a unitary structure, including: a substantially Z-shaped element of rigid construction, its horizontal portions constituting platforms; a depending ladder engaging hook at the free end of each horizontal portion; and an outwardly extending downwardly projecting ladder engaging hook intermediate the ends of the slanting portion of said element.

4. Structure as specified in claim 3, and an upstanding flange carried by the connected end 10 of the upper platform portion.

THOMAS E. GRAHAM.
